RICHARD GREENLEAF TURNER AND VICTOR H. JENNINGS, OF WORCESTER, MASSACHUSETTS, ASSIGNORS TO CROMPTON & KNOWLES LOOM WORKS, OF WORCESTER, MASSACHUSETTS, A CORPORATION OF MASSACHUSETTS

SHUTTLE CHANGING LOOM

Application filed December 26, 1931. Serial No. 583,242.

This invention relates to improvements in shuttle changing looms and it is the general object of the invention to insure the retention of an indication which is given by the weft detector mechanism.

In the type of shuttle changer loom to which this invention relates there is employed a regularly moving actuator to be connected to the changing device when the running weft is depleted. When an electrical weft detector is employed vibration of the part which closes the circuit may cause interruption of the detector circuit. Because of this condition exhaustion of weft may be indicated momentarily and then the indication lost before the actuator has time to move into engagement with the changing mechanism.

It is an important object of our invention to provide a temporary lock which becomes effective when contact is first made to hold the actuator in operating position so that if the circuit should become broken the actuator will be held by the lock. In this connection it is still another object of our invention to provide a self-clearing lock so controlled as to retain the actuator in locked position on its working stroke, but acting to release or unlock said actuator on the non-rocking stroke.

With these and other objects in view which will appear as the description proceeds, our invention resides in the combination and arrangement of parts hereinafter described and set forth in the claims.

In the accompanying drawings, wherein a convenient embodiment of our invention is set forth,

Fig. 1 is a side elevation of the lower part of the loom provided with our invention,

Fig. 2 is a top plan view of the structure shown in Fig. 1, parts being omitted,

Fig. 3 is a front elevation of the latch on the actuator, showing said latch in non-operating position,

Fig. 4 is a view similar to Fig. 3 but showing the latch locked preparatory to the changing operation of the loom,

Fig. 5 is a detail plan view taken in the direction of arrow 5, Fig. 4, and

Fig. 6 is a fragmentary detail view similar to a part of Fig. 4, showing the parts in a different position.

Referring to the drawings, we have shown a loom frame 10 and a bottom shaft 11 having mounted thereon a track cam 12. The latter coacts with roller 13 mounted on an actuator lever 14 pivoted about a fixed stud 15. The cam has a complete revolution preferably every second pick of the loom and acts to raise the forward end 16 of the lever 14 at that point in the cycle of the loom operation when shuttle changing is about to begin, or when the lay is substantially at front center.

Pivoted on the stud 15 is a second lever 20 the forward end of which carries a stud 21 yieldingly held between link members 22 and 23 pivoted together as at 24. A tension spring 25 holds said members together in a manner similar to the connections employed on certain types of drop box motions. The lower end of link 22 is connected as at 26 to a block 27 which is operatively connected to the bottom of a box lifter rod 28. The latter has a nut 29 adjustable thereon to engage a surface of the rocker iron 30 which moves about axis 31 of the lay.

When the lever 20 is raised a lifting force is transmitted through the stud 21 and links 22 and 23 to the stud 26, which in turn raises the rod 28. Any sticking on the part of the said rod will result in expansion of the spring 25 to release the rod 28 from stud 21 and prevent breakage. The invention is shown in connection with a multicolor shuttle changing loom which employs cams 35 and 36, respectively, to coact with levers 37 and 38, respectively, through the media of which the selected shuttle is advanced to changing position.

The matter thus far described of itself forms no part of our present invention.

In carrying our invention into effect, we mount on the forward end of lever 16 a dog or latch 40 normally held in the position shown in Fig. 3 by a compression spring 41 interposed between said dog and the lever 16. The lower end of the latch is attached by means of a link 42 to the core 43 of a solenoid 44. The latter may be fed current by

means of wires 45 and 46, respectively, which are placed in circuit with a source of electric power when a change of shuttles is desired. The upper end of the dog has a head 47 provided with an inclined face 48 which extends upwardly and terminates in a point 49. A finger 50 projects upwardly from the latch and assists in the locking operations to be described.

- 10 The lever 20 is provided with a notch 51 defined by an overhang 52. As shown in Fig. 4 the lever 20 may have secured thereto a small supporting bracket 53 to which is adjustably secured horizontally a spring hook 54. The position of the latter with respect to the lever 20 may be determined by an adjusting screw 55 which locates the bracket 53, and said spring is provided with an upturned hook 56 to cooperate with the finger 50. The finger 50 has a horizontal extension 57 which is positioned to slide along inclined face 58 of the spring 54, the latter snapping up behind the horizontal part 57 to hold the latch or dog locked in 25 indicating position.

In operation, the parts will be in the relative position shown in Fig. 3 so long as sufficient weft in the running shuttle is present for continued weaving, the cam acting to 30 raise the dog every second pick of the loom without engaging the lever 20. When an indication of weft exhaustion is given by the detector, however, the solenoid 44 will be energized to attract its core 43 and thereby 35 rock the dog or latch 40 about its pivot 60 carried by the lever 16. When the latch rocks, the offset part 57 of the finger 50 will move up the inclined face 58 to depress the spring, and thereafter permit the latter to 40 snap upwardly into the locking position shown in Fig. 4. In this position the finger is held by the hook and the pointed end 49 is beneath the notch 51. Should the contact in the detector be broken due to loom vibration, the current flowing through the solenoid will be interrupted, but this will not affect the position of the latch because the latter is held by the spring hook or lock.

When the transfer movement actually 50 starts the cam will give lever 16 a rapid upward movement the effect of which will be to cause the point 49 to enter the notch 51 and thereby operatively connect the levers 16 and 20. Continued upward movement of 55 the lever 16 will raise the box rod 28 by the connections previously described to effect exchange of shuttles by means of rising boxes not shown but similar to those set forth in Patent No. 1,753,233. Further operation of 60 the loom will turn the cam to effect downward movement of the lever 16, but the downward movement need not be as fast as the upward movement.

The manner of maintaining and releasing 65 the lock will be described in connection with

Figs. 3, 4 and 6. When the dog or latch 40 moves from the position in Fig. 3 to that shown in Fig. 4 in response to energization of the solenoid 44, the point 49 will be spaced slightly from wall 65 which defines the vertical part of the notch 51, but said latch will move far enough to interconnect the finger 50 and the spring 54. The spring 41 is thus held stressed and acts with a constant tendency to return the dog to normal position. 70 During the quick upward movement of lever 16 the inclined face 48 will engage inclined face 66 of the notch, the effect of which will be to move the parts to the position shown in Fig. 6. This movement of the inclined surfaces will disengage the finger and hook so that the same will be spaced slightly, and also the bent end 57 of the finger will extend above the hook 56.

Further upward movement of lever 16 will couple the same with lever 20, and the levers will move the rod 28 to the desired position, after which they will begin their descent. When the stop nut 29 on the rod 28 engages the rocker iron further downward movement of lever 20 and hook 56 will be prevented. Lever 16 moves rather slowly at this time, however, so that as it continues to descend, spring 41 has an opportunity to swing the latch and dog in clockwise direction to move the end 57 over the hook. This disengagement of the locking feature is accompanied by a sliding of inclined face 48 along face 66. It is to be understood that these operations take place when the exhausted shuttle is in such a position that it cannot maintain a circuit through the solenoid, so that the latter does not oppose the action of spring 41.

From the foregoing it will be seen that we 105 have provided a simple means for retaining a setting of the actuator dog which may be set by a momentarily closed circuit, and that this circuit may be broken due to vibration of the loom or any other cause as soon as the latch has moved to the locking position shown in Fig. 4 without loss of the indication. It will also be seen that the effect of the inclined faces 48 and 66 is to cause a 110 slight relative movement of the locking finger and hook at the beginning of the upward movement of the lever 20 to insure separation of these parts, thus rendering impossible the raising of the hook by the finger. It will further be seen that the locking members act in such a way as to unlock themselves on the downward movement of the levers, this unlocking being brought about by having the actuator lever move rather slowly as it descends but movable fast enough as it ascends not to lose the locking effect. We 115 find that the arrangement of the latch in transmitting a vertical force is better than the previously used latch which slides in a horizontal plane.

Having thus described our invention it will be seen that changes and modifications may be made therein by those skilled in the art without departing from the spirit and 5 scope of the invention and we do not wish to be limited to the details herein disclosed, but what we claim is:

1. In a shuttle changing loom, an actuator to have a working stroke, a normally inoperative member effective when moved to assist in the shuttle changing operation, means movable at weft exhaustion and prior to a working stroke of the actuator to shuttle changing position to operatively connect the 10 actuator and member when the actuator has a working stroke, and a lock to hold the means in shuttle changing position after being moved to said position and until the actuator has its working stroke.
2. In a shuttle changing loom, an actuator to have a working stroke, a normally inoperative member effective when moved to assist in the shuttle changing operation, means movable at weft exhaustion and prior to a 15 working stroke of the actuator to shuttle changing position to operatively connect the actuator and member when the actuator has a working stroke, and a lock to hold the means in shuttle changing position after being moved to said position and until the actuator has its working stroke, the actuator effective on its working stroke to move the lock to unlocking position.
3. In a shuttle changing loom, an actuator 20 to have a working stroke, a normally inoperative member effective when moved to assist in the shuttle changing operation, means movable at weft exhaustion and prior to a working stroke of the actuator to shuttle changing position to operatively connect the actuator and member when the actuator has a working stroke, and a lock to hold the means in shuttle changing position after being moved to said position and until the actuator has its working stroke, said lock formed of two parts one of which is carried by the member, and relative movement of the actuator and member effective to move the parts to unlocking position.
4. In a shuttle changing loom, an actuator 25 to have a working stroke, a normally inoperative member effective when moved to assist in the shuttle changing operation, means movable at weft exhaustion and prior to a working stroke of the actuator to shuttle changing position to operatively connect the actuator and member when the actuator has a working stroke, and a lock to hold the means in shuttle changing position after being moved to said position and until the actuator has its working stroke, said lock formed of two coating parts, one carried by the means and the other by the member, relative movement of the actuator and member effective to 30 move the parts to unlocking position.

5. In a shuttle changing loom, an actuator to have a working stroke, a normally inoperative member effective when moved to assist in the shuttle changing operation, an electro-magnetic device to be actuated at weft exhaustion, a latch responsive to the device and movable thereby prior to a working stroke of the actuator to shuttle changing position where it will be effective to interconnect the member and actuator when the latter has a 70 working stroke, and a lock to retain the latch in shuttle changing position independently of the electro-magnetic device, the lock rendered effective by the device.

6. In a shuttle changing loom, an actuator having a working stroke and a non-working stroke, a normally inoperative member effective when moved to assist in the shuttle changing operation, a latch capable of connecting the actuator and member to cause 80 them to move together, yielding means normally holding the latch out of shuttle changing position, a device operative at indication of weft exhaustion to move the latch against the yielding means to shuttle changing position where said latch is effective to connect the actuator and member, and a lock to hold said latch in shuttle changing position from the time the latch is moved to shuttle changing position until the actuator starts its next 85 working stroke.

7. In a shuttle changing loom, an actuator having a fast working stroke and a slow non-working stroke, a normally inoperative member to be moved by the actuator to assist in the shuttle changing operation, a latch urged normally away from shuttle changing position, but movable at indication of weft exhaustion to shuttle changing position and capable when in said position to interconnect the member and actuator when the latter has a working stroke, and a lock to hold the latch in shuttle changing position, said lock including a part moved by the latch and a part moving with the member, the parts to be disengaged on the working stroke of the actuator, but the fast motion of the latter preventing the latch from moving away from shuttle changing position before the latch engages the member, and the latch disengaging itself from the member during the subsequent slow non-working stroke of the actuator.

8. In a shuttle changing loom, an actuator having a fast working and a slow non-working stroke, a normally inoperative member effective when moved to assist in the shuttle changing operation, a latch carried by the actuator, yielding means normally holding the latch out of shuttle changing position, means responsive to an indication of weft exhaustion to move the latch into shuttle changing position where it is effective to connect the member and the actuator when the latter has a working stroke, and a lock comprising two parts one of which is moved by the latch and 125

the other of which is supported by the member, said lock to hold the latch in shuttle changing position and movable to unlocking position by a working stroke of the actuator,
5 the latch on the working stroke due to the fast movement of the actuator engaging the member after the lock is unlocked before the yielding means moves the latch away from shuttle changing position, said latch on the
10 subsequent slow non-working stroke of the actuator being movable by the yielding means away from shuttle changing position before said parts are able to interact and again lock the latch in shuttle changing position.
15

In testimony whereof we have hereunto affixed our signatures.
